UNITED STATES PATENT OFFICE

JAMES W. BRYCE, OF BLOOMFIELD, NEW JERSEY, ASSIGNOR TO INTERNATIONAL TIME RECORDING COMPANY OF NEW YORK, OF ENDICOTT, NEW YORK, A CORPORATION OF NEW YORK

DELINQUENCY SIGNALING SYSTEM

Application filed June 21, 1924. Serial No. 721,503.

This invention relates to systems for indicating or recording, or both, the performance, or non-performance, or both, of his duties by a watchman.

5 One of the objects of the invention is to provide a system in which the failure of a watchman to perform his duty is indicated by signal means.

Another object is to provide a system in 10 which the failure of a watchman to make his records at the proper time in accordance with a predetermined program is indicated by signal means.

Other objects and advantages will appear 15 as the invention is hereinafter disclosed.

Referring to the drawings which illustrate what I now consider preferred forms of the invention:

Fig. 1 is a front elevation of a casing, with 20 its door open, containing a program instrument and certain other auxiliary apparatus employed in the system.

Fig. 2 is an enlarged, fragmentary, detail elevation illustrating a part of the program instrument.

Fig. 3 is a plan view of the structure shown in Fig. 2.

Fig. 4 is a view similar to Fig. 3 but illustrating a different part of the program instrument.

Fig. 5 is a diagrammatic view illustrating the electrical connections of one form of the system.

Fig. 6 illustrates the mechanism which is 35 operable by the operating handle of an autographic recorder for producing a time record with the recorder and for causing the advance of the record strip.

The particular system illustrated in Figs. 40 1 to 6 inclusive comprises a program instrument, an autographic recording instrument, and electrical translating devices, signaling means, and connections which I shall now proceed to describe in the order named.

45 *Program instrument*

This instrument comprises a wheel 10 adapted to be rotated once in, say, twenty-four hours. This may be accomplished in a usual manner by means of an electromagnet

11, (Fig. 5) energized periodically, say once a minute, and connected by suitable pawl and ratchet means (not shown) to operate the wheel 10 step-by-step. The periodic energization of the electromagnet 11 may be conveniently effected by a circuit traced as follows: from the storage battery, or other suitable source of E. M. F., 12, to terminal 14, through the conductors 16, 17, 18, the coils of the electromagnet 11, conductor 19, resistance 20, conductor 22, to terminal 15, thence to contacts 13 (adapted to be closed and opened periodically, say once a minute, by a master clock mechanism similar to that shown in the United States Letters Patent No. 65 1,390,018), to the storage battery 12. By virtue of these instrumentalities it will be understood that the wheel 10 is a time-controlled wheel and, in the present embodiment, makes one revolution in twenty-four hours. 70

The wheel 10 is shown provided with a slot or groove 23 (Figs. 1 and 2) in which are adjustably mounted a plurality of cam lugs 24. As the wheel 23 rotates, counter-clockwise in Figs. 1, 2 and 5, each of the cam lugs 24 engages the end of an arm 25 (Fig. 3) which is pivotally mounted at 26 on the panel board 27 or a plate secured thereto. This engagement of any lug 24 with the end of the arm 25 causes the latter to be elevated, in opposition to the pull of its biasing spring 27, to cause an electrical contact 28, carried by said arm 25 but insulated therefrom, to engage a contact 29, carried by but insulated from an arm 30 similar to the arm 25, but shorter, and similarly mounted. In short, each of the lugs 24 causes the normally open contacts 28, 29, to close once in each rotation of the wheel 10. The time when the contacts 28, 29, will be closed by any particular lug or lugs 24 may be selected at will by properly adjusting the lug or lugs in the slot 23, the wheel 10 being calibrated with time-indicating graduations (Fig. 1) to aid in so setting the lugs 24. A similar set of lugs 31 are each adapted to close normally open contacts 32, 33, carried by but insulated from their respective arms 34, 35. The lugs 31 and instrumentalities operated thereby are substantially identical 95

to the lugs 24 and instrumentalities operated thereby, except that the lugs 31 are offset at their outer ends so that the lugs 24 cause closure of only the contacts 28-29 and not the contacts 32-33, and the lugs 31 cause closure of the contacts 32-33 and not the contacts 28-29. After any lug 24 or 31 has passed from under the corresponding set of arms 25, 30, or 34, 35, the biasing springs return the arms to normal position against the stop pin 36, (Fig. 2) at which position the contacts are open. Electric current may be conveyed to each of the contacts 28, 29, 32, 33, by means of flexible leads each connected to a corresponding one of the binding posts or terminals 37, 38, 39, 40 (Figs. 1 and 5).

While not indispensable, I prefer to provide a calendar wheel and contacts controlled thereby. This wheel is shown at 41 and is connected through suitable gearing to the 24 hour wheel 10 so as to rotate once in a week. This wheel or disk 41 is shown provided with two circumferential rows of holes 52 into which pins or pegs 42, 43, (Fig. 4) are adapted to be inserted or removed at will. The pins 42, 43, are adapted respectively to cause closure of the normally open contacts 44-45 and 46-47 which are carried by arms similar to the arms 25, 30, 34, 35, described above. Binding posts 48 to 51 may be provided for the contacts 44, 45, 46, 47, and connected thereto by suitable flexible leads. By proper disposition of the pins or pegs 42, 43, in the holes 52, the contacts 44-45 and 46-47 may be closed for six, twelve, eighteen or twenty-four hours of any desired day or days of the week.

To facilitate explanation of the invention, it may be assumed that the pegs 42, 43, are adjusted so as to cause the contacts 44-45 and 46-47 to be closed from midnight until 6 a. m. on each week-day but not Sunday, and that the lugs 24 are so adjusted as to cause the contacts 28-29 to close momentarily at midnight, and momentarily on each hour thereafter, and that the lugs 31 are so adjusted as to cause the contacts 32-33 to close momentarily at 12:20 A. M., 1:20 A. M. and so on, i. e., twenty minutes after each closure of the contacts 28-29.

Autographic recording instrument

This instrument is known in the art and may be of the type disclosed in U. S. Patent No. 1,327,334, which includes provisions whereby a person may sign his name and then, by depressing a handle, cause a record of time to be made. Such an instrument is indicated at 60 in Figs. 5 and 6 and in this instrument I provide a pair of normally closed contacts 63, 64, adapted to be opened by engagement of the arm 62 (connected to the handle 61) with the contact 63. Normally the contacts 63-64 are closed but they are momentarily opened by depression of

the handle 61, which handle is employed to effect the time record or records in the autographic recorder 60.

Auxiliary apparatus and electrical connections

When the contacts 28-29 close, and the contacts 44-45 are closed, the following circuit is established: from the battery 12, through the contacts 13 (which close momentarily once a minute), terminal 15, conductor 22, the coil of a relay 65, a resistance 66, conductor 67, binding post 37, contacts 28-29, binding post 38, conductor 68, binding post 49, contacts 44-45, binding post 48, conductor 69, conductor 16, terminal 14, back to battery 12. The closure of the last traced circuit energizes the relay 65.

Energization of the relay 65 causes closure of the following circuit: from one side of the power line 70, conductor 71, conductor 72, front contacts of relay 65, conductor 73, resistance 74, conductor 76, coil of relay 77, conductor 78, terminal 79, conductor 80, contacts 64-63, conductor 81, terminal 82, conductor 83, to the other side of the power line 84. When this last traced circuit has been closed by closure of the front contacts of the relay 65, the circuit through the coil of the relay 77 remains closed (by virtue of a stick or holding circuit formed by the front contacts 85-86 which are in parallel with the front contacts of the relay 65) even after the front contacts of the relay 65 have opened. The complete stick or holding circuit may be traced as follows: from line wire 70, conductor 71, front contacts 85-86 (now closed by energization of the coil of the relay 77), conductor 73, resistance 74, conductor 76, coil of relay 77, conductor 78, terminal 79, conductor 80, contacts 64-63, conductor 81, terminal 82, conductor 83, to the other line wire. It will be noted that when the coil of the relay 77 is energized it can be deenergized only by opening of the contacts 64-63, i. e., by depression of the handle 61 of the autographic recorder to effect a time record.

Unless the coil of the relay 77 has been deenergized, by opening of the contacts 64-63, the following circuit is closed by closure of the contacts 32-33 of the program instrument: from line wire 70, through conductor 71, front contacts 85-86 of relay 77, front contacts 90-91 of the same relay, conductor 92, binding post 50, contacts 46-47, binding post 51, conductor 93, binding post 40, contacts 33-32, binding post 39, conductor 94, resistance 95, conductor 97, coil of relay 98, conductor 78, terminal 79, conductor 80, contacts 64-63, conductor 81, terminal 82, conductor 83, to the other line wire 84. When the coil of the relay 98 is energized, the following stick or holding circuit is closed: from line wire 70, through conductor 71, conductor 100, front contacts 101-102 of the

relay 98, conductor 94, resistance 95, conductor 97, coil of relay 98, conductor 78, terminal 79, conductor 80, contacts 64—63, conductor 81, terminal 82, conductor 83, to the other line wire 84. Once this stick circuit is closed it can be opened only by opening the contacts 64—63, i. e., by depression of the handle 61 to effect a time record in the autographic recorder 60.

10 Energization of the coil of the relay 98 causes closure of the following circuit: from the line wire 70, through the conductors 71, 100, front contacts 101—102 and 105—106 of the relay 98, conductor 107, double pole switch 108, conductor 109, terminal 110, conductor 111, signaling device 112 (in the present case an electric bell), conductor 113, terminal 114, conductor 115, conductor 116, to the other side 84 of the line.

20 It will now be appreciated that after the coil of the relay 77 has been energized, the relay 98 will be energized and the alarm 112 sounded upon closure of the contacts 32—33 and 46—47 of the program instrument, unless the handle 61 has been depressed to open the contacts 64—63 (hereby to deenergize the coil of the relay 77) prior to the closure of the contacts 32—33. If the contacts 64—63 have been opened, by the depression of the handle 61, prior to the closure of the contacts 32—33, the coil of the relay 98 will not be energized upon the closure of the contacts 32—33 because the pick-up circuit of the coil of the relay 98 will be open at the contacts 39 90—91 of the relay 77, the latter having been deenergized by the opening of the contacts 64—63. After the coil of the relay 98 has been energized it will remain energized, and the bell 112 will continue to ring, until the contacts 64—63 are opened.

40 In order that the invention may be connected at 70—84 with the usual 110 volt D. C. or 110 volt A. C. at 65, 50, 40, or 25 cycles, I provide the resistances 74 and 95 with taps leading to terminals 120, 121, 122, 123, 124, and terminals 127, 128, 129, 130, 131, respectively, and I connect the conductors 76 and 95 97 to the terminals 125 and 126 respectively. If the voltage at 70—84 is 110 volts D. C. the terminal 125 should be connected with the terminal 124, and the terminal 126 should be connected with the terminal 127. For 110 volt A. C. the connections should be as follows for the various frequencies:

Frequency, cycles per second	Terminal 125, connected to—	Terminal 126, connected to—
25	123	128
40	122	129
50	121	130
60	120	131

As shown in Fig. 1, all of the various instrumentalities shown in Fig. 5; with the exception of the autographic recorder 60,

the signal 112, the storage battery 12, and the master clock contacts 13; are mounted within a panel box or casing 150, having a hinged cover or door 151 which may be provided with a lock (not shown) to prevent unauthorized access to the casing-contained mechanism.

The casing 150 may be mounted at any convenient location in a plant to be supervised, the autographic recorder 60 is mounted 75 at some place where the watchman must pass and sign up in making his rounds. For example, suppose a watchman's system employs thirty stations.

General description of operation

80

The arrangement may be such that the watchman makes a round of a group of, say, ten of these stations so arranged as to bring him back to the location of the autographic recorder where he would sign up and depress the handle 61; he may then make a round of the second group of, say, ten stations so arranged as to bring him back to the location of the autographic recorder where he would sign up and depress the handle 61; and he may then make a round of the third group of, say, ten stations so arranged as to bring him back to the location of the autographic recorder where he would sign up and depress the handle 61; and he may then repeat the above cycle. Under the set-up on the program instrument assumed above, the watchman would make his first round of ten stations at midnight. He would have twenty minutes in which to complete that round and then sign up and depress the handle 61 of the autographic recorder 60. If he fails to depress the handle 61 within the time allowed the bell 112 will ring and continue to ring until the handle 61 is depressed. At 1:00 a. m. the watchman would begin his second round of stations and would have twenty minutes in which to complete this round and operate the autographic recorder 60; and so on.

If desired, the various stations may be key stations of a watchman's portable time clock system.

The alarm 112, or as many as are provided, are in practice located on the outside of the property being watched and the police advised of the purpose thereof and notified to investigate the premises immediately if at any time the signaling means are operating. If through accident, violence, or neglect of duty, the watchman fails to follow and conform to his schedule of rounds, the signaling means 112 will be automatically set in operation.

By virtue of the adjustability of the cam lugs 24 and 31, it is not necessary that the stations be divided equally into rounds nor that the rounds consume equal lengths of time, for example, the schedule on the pro-

gram instrument may be set up to allow the watchman ten minutes on one round, twenty minutes on another, fifteen minutes on a third, and so on.

As explained, registering on the auto-graphic recorder after the completion of a round resets the system for the next round. By virtue of the adjustability of the lugs 24 and 31, it is not only possible to start the rounds at any desired times, and to provide for rounds of different lengths, but different extra allowances of time to provide for delays may be made.

It will be appreciated that the invention may not only be employed in connection with watchmen who guard against fire or theft but also wherever it is necessary or desirable that a person or persons visit certain localities at predetermined times, for example, the superintending of machines. I therefore wish it to be understood that when I employ the word "watchman" I do not mean to include only watchman against burglarly or theft but I mean to include any person charged with the duty of being at certain places at predetermined times or within predetermined time limits.

In accordance with the provisions of the patent statutes, I have herein described the principle of operation of my invention, together with the apparatus which I now consider to represent the best embodiments thereof.

What I claim is—

1. In a system of the class described, in combination, a recording device located at an area to be supervised and adapted to be actuated by a watchman in making his rounds, signaling means, and inaccessible means controlled by said device for preventing operation of said signaling means provided the watchman actuates said device at a predetermined time and makes a proper record upon the recording device at the area to be supervised which shows that the watchman has operated the recorder in time to prevent operation of the signal device.

2. In a system of the class described, in combination, a recording device located at an area to be supervised and adapted to be actuated by a watchman in making his rounds, signaling means, means for automatically operating said signaling means if the watchman fails to actuate said device within a predetermined time interval, and inaccessible means controlled by said device for preventing operation of said signaling means provided the watchman actuates said device within said predetermined time interval and makes a proper record upon the recording device at the area to be supervised which shows the presence of the watchman at the recording device and the operation by him of the recording device at a time when signaling would occur unless prevented.

3. In a system of the class described, in combination, signaling means, time-controlled means for automatically placing said signaling means in operative condition at predetermined different successive time intervals, means comprising a device adapted to be operated by a watchman in making rounds of different permissible time intervals for preventing operation of said signaling means by operation of said device at predetermined times prior to the expiration of said predetermined different time intervals, and means also controlled solely by said same device for discontinuing the operation of said signaling means after it has been automatically placed in operative condition, said last mentioned means being effective for control to discontinue the signal after any predetermined time interval for preventing operation of the signal has passed.

4. In a system of the class described, in combination, signaling means, time-controlled means for automatically placing said signaling means in operative condition at predetermined times according to a program which may be preset for successively variable different time intervals, a recording device located at an area to be supervised and adapted to be actuated by a watchman in making his rounds, and inaccessible means controlled by actuation of said recording instrument in the making of a time record thereby and therein and in accordance with the predetermined program schedule for preventing operation of said signaling means and for also recording by the recorder the time when the signaling operation was prevented by such actuation.

5. In a system of the class described, in combination, electric signaling means and a circuit for energizing the same, time-controlled means including a second circuit for controlling the closing of said first named circuit at the expiration of predetermined time intervals, means comprising a device adapted to be actuated by a watchman in making his rounds for preventing closure of said first named circuit, said last named means also being adapted to open both of said circuits after said first named circuit has been closed.

6. In a system of the class described, in combination, signaling means, a manually operable recording instrument located at the area to be supervised to be visited and operated by a watchman to effect a record between rounds of different distances and correspondingly different permissible time durations, a program instrument having devices operative at successively different time intervals to correspond to the times in advance of which the watchman is to operate the recording instrument between said rounds, and means under the control of said devices of the program instrument for causing said signal-

ing means to operate unless the same recording instrument is in each case operated within the different time intervals determined by the devices of the program instrument.

5 7. In a system of the class described, in combination, signaling means, a manually operable device adapted to be operated by a watchman in making his rounds, a program instrument, means under the control of said program instrument for causing said signaling means to operate unless said device is operated by the watchman in accordance with the program determined by said program instrument, said last named means also being 10 adapted to open said circuit after said circuit has been closed.

8. In a system of the class described, in combination, a program instrument, a group of circuits adapted to be closed periodically 20 by said program instrument, a relay in one of said circuits for maintaining said circuit closed, a device adapted to be operated by a watchman in making his rounds for opening said one circuit of said group of circuits, a second group of circuits adapted to be closed by the energization of said relay and the cooperative operation of said program instrument at a predetermined time, and a signaling means in a circuit of said last named 25 group of circuits to indicate whether or not said device has been operated.

9. In a system of the class described, in combination, a program instrument, a group of circuits adapted to be closed periodically 35 by said program instrument, a relay in one of said circuits for maintaining said circuit closed, a second group of circuits adapted to be closed by the energization of said relay and cooperative operation of said program 40 instrument at a predetermined time, signaling means in a circuit of said last named group of circuits, and a device adapted to be operated by a watchman in making his rounds for opening said last named group of circuits 45 should the watchman have failed to operate said device prior to said predetermined time.

10. In a system of the class described, in combination, a program instrument, a group of circuits adapted to be closed periodically 50 by said program instrument, a relay in one of said circuits for maintaining said circuit closed, a second group of circuits adapted to be closed by the energization of said relay and cooperative operation of said program 55 instrument at a predetermined time, signaling means in a circuit of said last named group of circuits, and a device adapted to be operated by a watchman in making his rounds for opening either of said two groups 60 of circuits.

11. In a system of the class described, in combination, a program instrument, a controlling circuit, means controlled by said program instrument for closing said controlling circuit at a predetermined time, manipulative 65

means adapted to open said controlling circuit, a second controlling circuit adapted to be closed by said program instrument at a predetermined time, and an alarm circuit adapted to be closed by said second controlling circuit at said last mentioned predetermined time. 70

12. The combination set forth in claim 11 in which the manipulative means is adapted to open the second named controlling circuit. 75

13. In a system of the class described, in combination, a program instrument, a controlling circuit adapted to be closed by said program instrument at a predetermined time, a second controlling circuit under the 80 control of said first named controlling circuit and adapted to be closed by said program instrument at another predetermined time, an alarm circuit adapted to be closed at said latter predetermined time, and means 85 for opening said first named controlling circuit so as to prevent closing of said alarm circuit.

14. In a system of the class described, in combination, means for producing an alarm 90 at a predetermined time under set conditions including a plurality of circuits, a program instrument for causing energization of one of said circuits during a time interval preceding said predetermined time and for causing 95 energization of another of said circuits at the termination of said time interval and a device capable of causing discontinuance of the energization of said circuits during said time interval, and an alarm circuit under the control of said circuits for causing an alarm to be sounded subsequent to said time interval provided said device has not been previously operated. 100

15. In a system of the class described, in combination, means for causing an alarm to be sounded at a predetermined time under certain conditions including a plurality of circuits, a program instrument for closing 105 said circuits at definite times, an alarm circuit adapted to be closed at a predetermined time when said circuits are closed, and manipulative means for opening at least one of said circuits whereby said alarm circuit is opened. 110

16. The combination set forth in claim 15 115 in which said manipulative means may open one of the circuits prior to the energization of the alarm circuit and thereby prevent sounding of an alarm.

17. In a system of the class described, in combination, a program instrument having means for controlling the closing of a controlling circuits, one of said controlling circuits being closed at the beginning of a time interval, and another of said circuits being 120 closed by and with said first controlling circuit at the end of said time interval, an alarm circuit under the control of said controlling circuits, and means for opening said first controlling circuit during said time interval and 125 130

for opening said second controlling circuit at the close of said time interval for the purposes described.

18. In a system of the class described, in combination, a device adapted to be actuated by a watchman in making his rounds, signaling means, program-controlled means for rendering said signaling means operative, and means controlled by said device for preventing operation of said signaling means provided the watchman actuates said device at a predetermined time, means called into operation by said program-controlled means for removing said signaling means from the control of said program-controlled means to continue an initiated signal, and means controlled by said same first mentioned device for discontinuing the operation of said signaling means subsequent to said predetermined time.

In testimony whereof I hereto affix my signature.

JAMES W. BRYCE.
